UNITED STATES PATENT OFFICE.

OTIS L. BLACKMAN, OF EVANSVILLE, WISCONSIN.

ROTARY ATTACHMENT FOR WINDMILLS, &c.

SPECIFICATION forming part of Letters Patent No. 232,875, dated October 5, 1880.

Application filed May 19, 1880. (Model.)

To all whom it may concern:

Be it known that I, OTIS L. BLACKMAN, of Evansville, Wisconsin, have invented a new and useful Rotary Attachment for Windmills, 5 Water-Wheels, and other Powers where it is desired to produce a rotary motion by means of a driving pitman-shaft working either in a vertical or a horizontal position.

The object of my invention is to overcome 10 the "dead-center" always found in a crank motion operated by a rod or pitman-shaft. I attain this object by means of the mechanism illustrated in the accompanying drawings, in which—

15 Figure 1 is a vertical view of the entire machine. Fig. 2 is a detailed side view of the double-slotted lever-head and lever at the top of the machine, and Fig. 3 is a view of a similar lever-head and lever at the bottom of the machine.

20 Similar letters refer to similar parts throughout the several views.

In Fig. 1 the revolving table A A and the standards B B B B constitute the frame-work supporting the whole machinery.

25 *a a* is a shaft connecting the machine to the power and resting in the long box *b*, which is fastened to the top of the revolving table A A. C is the rotating wheel fastened securely to shaft *a a*. D is the rotated wheel at the bottom of the machine. *c c* are small wrist-pin wheels fastened to the rear of wheels C and D. E E are double-slotted lever-heads working on the wrist-pin wheels *c c*, and forming 30 the ends of a connecting-rod, of which rod the swiveled hollow rod *d d* forms the middle. *e e* is the swivel in the connecting-rod, which allows the top of the rod to revolve while the bottom remains stationary. *f f* are the points 35 at which the ends E E are securely fastened to hollow rod *d d*. *g g* are wrist-pins fastened in the faces of wheels C and D, respectively. F F are the ends of rod working on the wrist-pins *g g*. These ends are connected by swiveled hollow rod *h h*, which passes through hollow rod *d d*. *i i* is a swivel in the hollow rod *h h*, and allows the top of the rod to revolve while the bottom remains stationary. *k k* is a 45 shipping-rod fastened at the bottom to spider G G, and, passing through the hollow rod *h h*, is connected at the top to the bottom of the

revolving table A A by the swivel *l l*, thereby keeping the hollow rods *d d* and *h h* in vertical position.

The swivels *e e*, *i i*, and *l l* allow the whole top 55 of the machine, supported by the revolving table A A, to revolve in either direction while the bottom remains stationary. *m* is a shaft connecting the rotated wheel D with the machinery to be driven. (Represented in Fig. 1 by the wheel H.) *n n* and *o o* are slots in the lever-heads E E. *p* is a ratchet-shaped lever fastened in the slot *n n* by the pin *r*, and is worked back and forth across the slot *o o* by shafts *a a* and *m*, and prevents the top of lever-heads E E from dropping on the wrist-pin wheels *c c*. 65

Power applied to shaft *a a* is carried to the wheel C, and, through the wrist-pin *g g*, is transmitted to rod F F, and by it to the wheel D 70 just before the wrist-pin *g g* arrives at the points known in mechanics as the "dead center." The wrist-pin wheels *c c* strike, alternately, the top of the slot *n n*, Fig. 3, taking the power from the rod F F, and, being connected to the wrist-pin *g g* by the wheels C and D, push said wrist-pin *g g* by the dead-center, when they again resume their work. 75

I am aware that prior to my invention rotary powers with two rods have been in use. 80 Therefore I do not especially claim the two-rod attachment; but

I do claim as my invention—

1. The combination of the device of the double-slotted lever-head E E, Figs. 2 and 3, 85 by placing slotted head E, Fig. 2, on shaft *a a*, between and in rear of rotary wheel C and end of long box *b*, and slotted head E, Fig. 3, on shaft *m*, between and in rear of reciprocating wheel D and end of shaft-box, and by aid 90 of wrist-pin wheel *c c* to work double-slotted lever-heads, and, acting in conjunction with rods F F, connected to rotary wheel C and reciprocating wheel D by wrist-pin *g g*, producing a reciprocal rotary motion corresponding 95 to the rotary power applied, substantially as shown, for the purpose specified.

2. The combination of the device of swiveling the two rods from a common center by the hollow rod *d d*, swiveled in the center *e e*, to 100 which the slotted heads E E are connected at *f f*, and the hollow rod *h h*, passing through

the hollow of the swiveled rod *d d* and swiveled at *i i*, connecting the rod *F F*, attached to rotary wheel *C*, reciprocating wheel *D*, attached to shaft *a a* and *m* by wrist-pin *g g*, the rod *5* and swivel stayed and supported in a vertical position by the hollow rod *k k*, fastened by spider *G G* to frame-work *B B* and bottom of turn-table at swivel *l*, and allowing the shipping-rod to pass unobstructed through center of shifting-pipe, thereby allowing the rotary power to revolve and ship in or out the wind while the reciprocating machinery remains stationary, substantially as set forth.

3. The combination of the wheel *c c* and the levers *p p*, to change a vertical or a horizontal 15 to a perfectly reciprocating rotary motion, substantially as described.

4. The combination of the lever-heads *E E*, the levers *p p*, and the wrist-pin wheel *c c*, for overcoming a mechanical dead-center in a crank 20 rotary motion, substantially as set forth.

OTIS L. BLACKMAN.
